(57) **CLAIM**

The ornamental design for a candle wrap with transparency gradient, as shown and described.

DESCRIPTION

FIG. 1 is a perspective view of a first embodiment of a candle wrap with a transparency gradient.

FIG. 2 is a front view of a first embodiment of a candle wrap with a transparency gradient, which is visually the same as the back view of the same embodiment.

FIG. 3 is a right side view of a first embodiment of a candle wrap with a transparency gradient, which is visually the same as the left side view of the same embodiment.

FIG. 4 is a top view of a first embodiment of a candle wrap with a transparency gradient, which is visually the same as the bottom view of the same embodiment.

FIG. 5 is a perspective view of a second embodiment of a candle wrap with a transparency gradient.

FIG. 6 is a front view of a second embodiment of a candle wrap with a transparency gradient, which is visually the same as the back view of the same embodiment.

FIG. 7 is a right side view of a second embodiment of a candle wrap with a transparency gradient, which is visually the same as the left side view of the same embodiment.

FIG. 8 is a top view of a second embodiment of a candle wrap with a transparency gradient, which is visually the same as the bottom view of the same embodiment.

FIG. 9 is a perspective view of a third embodiment of a candle wrap with a transparency gradient.

FIG. 10 is a front view of a third embodiment of a candle wrap with a transparency gradient, which is visually the same as the back view of the same embodiment.

FIG. 11 is a right side view of a third embodiment of a candle wrap with a transparency gradient, which is visually the same as the left side view of the same embodiment.

FIG. 12 is a top view of a third embodiment of a candle wrap with a transparency gradient, which is visually the same as the bottom view of the same embodiment.

FIG. 13 is a perspective view of a fourth embodiment of a candle wrap with a transparency gradient.

FIG. 14 is a front view of a fourth embodiment of a candle wrap with a transparency gradient, which is visually the same as the back view of the same embodiment.

FIG. 15 is a right side view of a fourth embodiment of a candle wrap with a transparency gradient, which is visually the same as the left side view of the same embodiment.

FIG. 16 is a top view of a fourth embodiment of a candle wrap with a transparency gradient, which is visually the same as the bottom view of the same embodiment.

FIG. 17 is a perspective view of a fifth embodiment of a candle wrap with a transparency gradient.

(Continued)

FIG. 18 is a front view of a fifth embodiment of a candle wrap with a transparency gradient, which is visually the same as the back view of the same embodiment.

FIG. 19 is a right side view of a fifth embodiment of a candle wrap with a transparency gradient, which is visually the same as the left side view of the same embodiment; and, FIG. 20 is a top view of a fifth embodiment of a candle wrap with a transparency gradient, which is visually the same as the bottom view of the same embodiment.

The dominant feature of my design resides in the transparency gradient of a candle wrap. In addition, the bottom edge of the wrap has a slight radius, as seen in FIGS. 2, 6, 10, 14, and 18. Moreover, FIGS. 1-20 all conform to a first shape. Each of the embodiments has a different opacity gradient, where each individual embodiment transitions from fully transparent at the top, to fully opaque some distance down from the top.
